UNITED STATES PATENT OFFICE.

EDWARD O. CUSHING, OF WAVERLY, MASSACHUSETTS.

BATON-METRONOME.

1,191,285.

Specification of Letters Patent. Patented July 18, 1916.

Application filed March 15, 1916. Serial No. 84,480.

To all whom it may concern:

Be it known that I, EDWARD O. CUSHING, a citizen of the United States, residing at Waverly, Massachusetts, have invented certain new and useful Improvements in Baton-Metronomes, of which the following is a specification.

The present invention relates to metronomes and relates more particularly to a new type of such instruments, in which an additional element, resembling in character and movement a baton, is used in combination with a swinging pendulum.

The instrument forming the subject of the present invention is what may properly be termed a baton metronome.

The principal object of the invention consists in providing a mechanical device comprising a specially constructed pendulum adapted to carry and impart rhythmical motion to a baton so as to cause the latter to move with a regular up and down motion marking the time and accent to be followed in the rendering of either vocal or instrumental music. So far as I am aware I am the first to provide a mechanical device having a baton member adapted to move with the even up and down motion similar to that of the baton of a musical director.

A further object of the invention consists in the provision of specially formed supporting means for metronomes of this type, which permit of its use in convenient places on or about a piano, organ, etc.

A still further object of the invention consists in the provision of certain improved structural features and adjustments the advantages of which will be apparent from the description thereof contained in the following specification.

With these and other objects in view, the invention consists in the combination and arrangement of parts more fully set forth in the following specification, illustrated in the accompanying drawings and more particularly pointed out in the appended claims.

In the drawings: Figure 1 is a front elevation of the invention. Fig. 2 is a side elevation. Fig. 3 is a horizontal transverse section on line 3—3 of Fig. 1. Fig. 4 is a perspective view showing a modified form of supporting base.

Referring to the drawing, particularly Figs. 1 to 3, the device is supported by a block 1 of wood or any suitable material.

The supporting block may be square, rectangular or of any desired configuration provided it is of sufficient size and weight to afford a firm and steady base. As the instrument is frequently placed on a piano 60 or organ, the underside of the supporting block is supplied with a felt covering to prevent injury to the polished surface of the wood. The supporting stand comprises a vertical rod or standard 2 adapted to have 65 its lower end fit in a circular hole 3 in the supporting block 1, and having its upper end bent at right angles to provide an arm or bracket 4 to the end of which a bearing yoke 5 is attached by a swiveled or set screw 70 connection 6. At each end of the prongs of the yoke 5 an upwardly turned pin or hook 7 is provided, which serve to support and retain the swinging members of the metronome. The body portion of the metronome 75 consists of a weighted member 8 of general arcuate shape, which is formed with a centrally located web terminating in an upright slotted member 8^a. A bearing pin 9^a passes transversely through the portion 8^a at right 80 angles and projects an equal distance on each side thereof. The pin 9^a rests loosely on pin 7 and permits a free oscillation of the weighted member 8 and its associated parts. Rigidly supported and fixed within the slot 85 of the upright member 8^a is a bar 9 having graduations marked thereon corresponding to the length of the beats, or the number of beats to the minute, which it is desired to have indicated. These graduations may indicate the number of oscillations or beats per minute and if desired, with the designations "andante," "adagio," etc. The graduations and figures are arranged in two columns. The left hand column requires a 90 down and up stroke for one beat, while the right hand column represents one beat with the down stroke and one beat with the up stroke. A slide or weight 10 resembling somewhat in contour the lower weighted 95 member 8 slides vertically up and down on the upright member 9 and is adapted to be clamped in any adjusted position by means of a set-screw 11. As the slide 10 is moved toward the upper part of the upright 100 9, the number of oscillations is diminished. The weighted arcuate member 8 is provided at its right hand end with a circular recess 8^b, in which a specially constructed baton 12 is adapted to be fitted. This baton attach- 105 110

ment resembles in shape and motion the ordinary baton used by an instructor or musical conductor for instrumental or vocal work.

5. The parts of this instrument can be made at very little cost and its construction is so simple that the device can be quickly and easily assembled. By having the yoke member 5 swiveled or adjusted with a set screw 10 the bearing pins 7 may always be placed in a horizontal plane even through the base block should be standing on an inclined or irregular surface.

15. In Fig. 4 a modified form of base block 1' is shown, which is formed with a concaved, upper surface 1² for the purpose of enabling it to be slid in under the music rest on the piano or organ, thus holding the metronome firmly directly in front of the person using 20 the instrument. By carefully graduating the scale on the upright member 9, the slide 10 can be positioned to secure any exact number of oscillations or beats of the baton 12, required in music.

25. What I claim is:—

1. In a metronome, the combination of a freely suspended weight member, an upright

bar extending therefrom, and a baton secured at one side of said weight member.

2. In a metronome, the combination of a 30 freely suspended weight member, an upright bar extending vertically therefrom, and a removable pointer or baton adapted to be carried at either side of said weight and extending horizontally therefrom. 35

3. In a metronome the combination of a freely suspended weight member, an upright bar extending vertically therefrom, a baton extending horizontally from said weight and a slide member adjustably carried on said 40 upright bar. 40

4. In a metronome the combination of a supporting stand, a swiveled bearing carried thereon, a weight member freely suspended from said bearing, a vertical graduated bar extending from said weight, a horizontally disposed baton removably attached at one side of said weight member. 45

In testimony whereof I affix my signature.

EDWARD O. CUSHING.
